BEAM CLAMP

John Pinaud, Atlantic Highlands, and George Quick, North Arlington, N. J., assignors, by mesne assignments, to Universal Form Clamp Company, Chicago, Ill., a company of Illinois

Application January 29, 1934, Serial No. 708,755

5 Claims. (Cl. 25—131.5)

This invention relates to a novel hanger construction for supporting molds into which concrete is poured.

In the construction of concrete buildings, especially the floor and ceilings, in which steel I-beams are embedded in the concrete or the like, it is the practice to hang a mold from certain of the steel beams by means of devices, the upper ends of which are adapted to be attached to the beams.

10 After the concrete is poured and allowed to set and harden, the molds are removed. The present invention has to do with the provision of improved devices, particularly adapted for this purpose, i. e., to hang the molds and to allow them to be readily removed after the concrete is poured. The improved devices may, however, be useful for other purposes.

Inasmuch as each such device (except its lower end) is embedded in concrete so that at least a portion of it has to remain in the ceiling or other concrete structure when the mold is removed, it is important that the device be simple and inexpensive to manufacture. At the same time, however, the devices should be capable of supporting a relatively heavy load, in order to avoid the use of excessive numbers of the devices.

Moreover, it is desirable that the portion of the device which engages the mold be severable from the portion which is attached to the beam, in order not to leave an end of the device protruding below the concrete. In addition, the devices should be capable of being readily assembled and secured to the mold and beam, preferably to a bottom flange of the latter.

35 A feature of the present invention resides in the provision of a device of this character which satisfies these requirements in a superior manner and at the same time achieves a number of other advantages among which are elimination of any tendency of the load to tip the clamp from its assembled position; reduction of swaying of the mold while concrete is poured; ease of disassembly when the mold is to be stripped off; uniform high quality and strength of the device, especially the portion which engages the beam; avoidance of need for spacers between the beams and the mold; and maintenance of a uniform distance between the bottom or soffits of the mold and the beams.

50 Other features and advantages of the invention will become apparent as the following detailed description of certain illustrative forms of the improvement proceeds, reference being had to the accompanying drawings wherein:

55 Fig. 1 is a perspective view, partly in vertical

section, of a mold supported by a device in accordance with the invention, concrete having been poured into the mold;

Fig. 2 is a perspective view, on enlarged scale, illustrating the details of one form of such device;

Fig. 2a is a horizontal section taken along the bottom web of the clamp member shown in Fig. 2, partly broken away;

Fig. 3 is a vertical section, partly broken away, through a construction similar to that shown in Fig. 2 but somewhat modified;

Figs. 3a and 3b are vertical sections through modified forms of the construction illustrated in Fig. 3;

Fig. 4 is a detail plan view illustrating a further modification of the construction shown in Fig. 2;

Fig. 5 is an elevation, partly in section, illustrating a mode of operation of the constructions shown in Figs. 2, 3 and 4;

Figs. 6, 7 and 8 are perspective views of other forms of device constructed according to the invention;

Fig. 9 is a vertical section through still another modification;

Fig. 10 is a plan view of the construction shown in Fig. 9.

Fig. 11 is a perspective view of another modification, also in accordance with the invention.

Referring first to Figs. 1 and 2, there is shown a ceiling construction including a series of steel I-beams 15 from which a mold 16 including a soffit 16' is supported while concrete is poured into it and allowed to set. The supporting device includes a clamp 17 and a depending hanger

18. The clamp, in the form shown in Figs. 1 and 2, may advantageously be formed of a single sheet of steel or other suitable material and include a pair of spaced upright portions 19 joined by a web 20.

Each of the portions 19 may be provided with vertical and horizontal reinforcing flanges 21 and 22, respectively, and has a slot 23, into which the edge of a generally horizontal flange 24 of I-beam 15 extends a sufficient distance to enable the member 11 to have a secure grip.

The walls 25 at the bottom of the slots are adapted to lie flat against the bottoms of the I-beams, and will thus be generally horizontal.

However, as best shown in Fig. 5, the forward portions 25' of walls 25 may be inclined downwardly as indicated at 25', and the upper walls

26 preferably taper upwardly and forwardly in order to facilitate assembly of the member with the beam. Extending generally at right angles to the slots 23 and preferably lying substantially to the slots 23 and preferably lying substantially

forward of the rear walls of slots 23 are grooves 27 adapted to receive a wedge member 28, the upper face of which bears against the upper edges of grooves 27 and the lower face of which bears against the flange 24 in order to maintain the member 17 in assembled position on the beam.

The web 20 is preferably provided with an elongated aperture 20' through which the upper end of member 18 extends, the aperture being arranged to permit swinging of member 17 during assembly, as shown in Fig. 5. A nut 29 may be threaded onto the member and rest on the web 20 between it and the flange 24, and preferably substantially directly below the wedge 28, thus avoiding movements tending to tip the device. The lower end of member 18 may advantageously be provided with an enlarged portion 30, for instance an eye, which serves the double purpose of supporting a cleat 31 beneath the mold and of forming an engagement for a lever when the member is to be removed after the concrete, or the like, has set. Where desired, washers 32 may be interposed between the enlarged portion 30 and the cleat 31 to provide a flat surface upon which the cleat may rest. A plurality of clamp and hanger devices may be employed at suitably spaced intervals along the lengths of the beams, on one or both sides of the same.

It will be understood from the foregoing that in order to assemble the construction it is merely necessary to pass the members or bolts 18 through the washers 32, cleats 31, the soffits 16' and webs 20, and then thread the nuts 29 onto the bolts to the proper extent, whereupon the device may be assembled with the beam by swinging the members 17 outwardly as shown in Fig. 5, raising the mold to proper position, and then swinging the members 17 over the edge of flange 24 and driving the wedges 28 home. By cutting away the members 17 as at 25', the assembly is permitted with thick beam flanges without undue clearance between the edges 26 and the beam flange.

The concrete or the like is then poured into the mold and allowed to set, after which the members 18 may be turned to unscrew them from the nuts 29, now firmly embedded in the concrete, and then pulled out, for instance by extending a pin through the eye and using it as a lever.

Turning to Fig. 3, there is shown a form of device in many respects similar to the device described. Instead of the eye 30, however, the lower end of member 18 is formed with a bolt head 33 and the upper end of the member is tapered or narrows at 34 from the plane where it enters the concrete to the plane where the threads commence, so that the member may be readily withdrawn after the concrete has hardened, without the need for applying so great a force as would otherwise be necessary to accomplish this result.

In Fig. 3a, a particularly firm grip on the beam flange 24 is attained by providing a washer 29' between the nut 29 and the bottom of member 17, so that the flat upper surface of the nut 29 engages the bottom of the beam flange below the wedge 28, the hanger member 18 preferably not protruding above the nut 29. In this way undesirable tipping of the member 17, as would permit it to fall from the beam, is avoided.

In Fig. 3b a similar result is accomplished by screwing up the bolt 18 until its end engages the under side of the flange 24, a clearance being provided between the member 17 and the under side of the flange.

The construction illustrated somewhat dia-

grammatically in Fig. 4 is in most respects similar to the forms described, but instead of a straight wedge, a wedge 28' curved in a horizontal plane is employed, with the additional advantage that tipping of the member 17 is avoided even though clearance is provided, as shown at 35 in Fig. 5, between the member 17 and wedge 28, as is desirable to permit ready assembly of the parts. At the same time the wedge will be restrained against turning or tipping.

The construction described thus provides an extremely simple and effective construction among the advantages, of which is that a direct downward pull is produced, acting through the engagement between the clamping device and the beam, the hanger member engaging the clamp substantially directly below the wedge and beneath the beam. Moreover, the clamping member 17 may be formed from a single sheet of metal, for instance annealed sheet steel, by known simple operations, and thus provides a uniformly strong unit which is superior to a casting. Each clamp may be capable of supporting a safe working load of a ton or more. Each size of device is capable of use with a number of different standard sizes of I-beams, through the use of different wedges, so that the device need not be stocked in many different sizes. The threads on the hanger member may be of such extent that the lower end of the hanger depends on a uniform distance in each unit, and as the clamping action takes place at the top of the flange while the lower edges of the slots in the clamping members bear against the beam, the spacing of the mold from the beams is accurately determined without the need for separate spacers. Owing to the rigid nature of the construction, sagging is avoided. Moreover, the hangers can be readily removed by unscrewing to loosen them and then drawing down. Once removed, they may be used again and leave only a neat round hole in the concrete which can be readily filled.

Referring to Fig. 6, there is illustrated a clamp 40, also formed of a single piece of sheet material, and including spaced, vertical portions 41 joined at their rear edges by a web 42. The portions 41 have slots 23 similar to those described in connection with Figs. 1 and 2, and also grooves 26 for receiving wedge 28. By locating the web 42 at the rear of the clamp 40, the bottom of the clamp is left open, thus permitting a hanger 43 to be pivoted by means of a soft pin 44 between the portions 41, with its top below the slots 23, so that the lower walls of the slots may engage the under side of the beam flange 24. For assembling the lower end of hanger 43 with a mold, the hanger may have a slot 45 adapted to cooperate with a key 46, notched on its under side and capable of supporting a washer 47, when assembled.

The operation and advantages of this form will be apparent from the foregoing, but it may be noted that the pin 44 is adapted to be sheared off by a downward pull on the hanger, which is of relatively stiff material.

In the construction shown in Fig. 7 a clamping member is formed similar to the one shown in Fig. 6, save that it is provided with projections 51 on which a hanger 52 (shown in dotted lines) may be supported. Flanges 53 may be employed to prevent the hanger from sliding off while the concrete is being poured. In stripping the mold a downward pull on the hanger is designed to shear the projections 51 from the member 50.

and preferably also from flanges 53, if these are too large to be drawn through the concrete.

In Fig. 8, a clamp 55 is illustrated having a web 56 at the top of the clamp and serving as a bearing for wedge 57. This form involves many of the advantages of the forms previously described, and is especially simple to make. It may be employed wherever the mold allows room to drive the wedge home.

10 In Figs. 9 and 10 a modification of the forms described is shown as including a clamping member 60 having slotted side portions 61 joined by bottom web 62. A hanger 63 extends through the web 62 and is threaded into collar 64. Its upper 15 end is pointed and abuts against the bottom of beam flanges 24, thus securing the clamp to the beam, after the parts are assembled and the hanger is secured up into the collar.

The form shown in Fig. 11 is similar to that 20 shown in Figs. 1 to 5, save that clamping member 65 is formed solid and hanger member 66 is threaded directly into the lower portion of the member 65.

It will be understood from the foregoing that 25 there is provided a novel beam clamp which is simple and inexpensive to manufacture and in which a minimum number of parts remain embedded in the concrete. Moreover, the construction is readily assembled and disassembled, and 30 is sturdy and secure in operation. Moreover, the pull of the load on the device is advantageously positioned. A minimum number of the devices are required for a given ceiling, and one size of device cooperates with a number of different sizes 35 of I-beams. The device requires no skill to employ and results in an automatic proper disposition of the mold in a short assembly time.

A particular advantage of the present construction resides in the simple device, a portion 40 of which may be left in the concrete, while another portion is removed or severed from the first portion when the mold is stripped after the concrete has hardened.

The terms and expressions employed are used 45 as terms of description and not of limitation, and there is no intention in the use of such terms of excluding equivalents of features or parts of them as fall within the spirit of the invention.

We claim:

50 1. In a device for supporting concrete molds and the like upon steel I-beams and the like, a member having a groove adapted to receive an edge of a generally horizontal flange of an I-beam, wedge means adapted to lie on said flange and being curved lengthwise thereof, said member being adapted to receive the wedge means, 55 a slot formed in said member, and a depending hanger having an end adapted to extend through said slot, said slot being constructed and arranged to enable the member to be swung into engagement with the flange of the I-beam while the hanger depends in a substantially vertical position.

2. As an article of manufacture, a clamping member formed as an integral metal unit and including opposite spaced portions joined by a web, said portions having slots formed therein for receiving an edge of an I-beam or the like, and said web having a slot for receiving an end of a depending hanger, the slots in said portions of the clamping member and the slot in the web being so proportioned so as to enable the clamping member to be swung in a plane perpendicular to the length of the I-beam for engaging the latter while the hanger depends in a generally vertical direction. 5

3. In a device for supporting a concrete mold or the like upon the flange of an I-beam or the like, a clamping member formed as an integral metal unit and including opposite spaced portions joined by a web, said portions having slots formed therein for receiving an edge of a flange of the I-beam, a wedge member adapted to co-operate with the clamping member and extending generally lengthwise of the I-beam, said wedge member being curved along its length and said clamping member having recesses formed for receiving the wedge, a hanger, and a slot 20 formed in the web of the clamping member for receiving the upper end of said hanger, said slot being constructed and arranged to enable the clamping member to be swung in a plane perpendicular to the length of the I-beam into engagement with the flange of the I-beam, whereby said clamping member may be swung into operative position while the hanger depends in a generally vertical direction. 30

4. In a construction of the character described, 35 for supporting a mold or the like on the flange of an I-beam or the like, a clamping member having a slot adapted to receive the edge of an I-beam, a hanger member comprising a rod threaded at its upper end, and a nut threaded 40 to receive the threaded portion of the rod, said clamping member being adapted to support said nut and to pivot in a plane perpendicular to the length of the I-beam while said rod lies substantially vertical. 45

5. In a device of the character described for supporting a mold or the like upon the flange of an I-beam or the like, a member having a recess adapted to be swung over and thus receive an edge of an I-beam, an opening formed in said 50 member for receiving a wedge, a wedge adapted to extend lengthwise of the I-beam and to seat snugly in said opening, said wedge being constructed and arranged to prevent tipping of the member about the I-beam when the wedge is assembled with the member, and a depending hanger pivotally connected with said member, whereby said member may be swung into engagement with the flange of the I-beam while the hanger depends in a substantially vertical 55 position. 60
